Primary Examiner — Kendra Leslie Hamilton*Assistant Examiner* — Michael Hoffman(74) *Attorney, Agent, or Firm* — Bridgeway IP Law Group, PLLC; Sang Ho Lee; Hyun Woo Shin(57) **CLAIM**

The ornamental design for a surgical training kit, as shown and described.

DESCRIPTION

FIG. 1 is a perspective view of a surgical training kit, showing our new design;

FIG. 2 is a front elevation view thereof;

FIG. 3 is a rear elevation view thereof;

FIG. 4 is a left side elevation thereof;

FIG. 5 is a right side elevation view thereof;

FIG. 6 is a top plan view thereof; and,

FIG. 7 is a bottom plan view thereof.

The dashed broken lines in the drawings show portions of the surgical training kit that form no part of the claimed design.

1 Claim, 7 Drawing Sheets(56)
